UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

TURBINE.

1,101,619.

Specification of Letters Patent. Patented June 30, 1914.

Application filed December 10, 1913. Serial No. 805,719.

To all whom it may concern:

Be it known that I, CHARLES W. DAKE, a citizen of the United States, residing at Chicago, in the county of Cook and State of Illinois, have invented a certain new and useful Improvement in Turbines, of which the following is a specification.

My invention relates to steam turbines and is illustrated diagrammatically in the accompanying drawings, wherein—

Figure 1 is a side elevation with parts broken away and parts in section; Fig. 2 is a section along the line 2—2 of Fig. 1.

Like parts are indicated by the same letter in both figures.

A is a turbine housing having the steam chest A¹ and exhaust pipe A² and containing a rotor A³ provided with buckets A⁴ mounted on a shaft A⁵.

A⁶ is a drip or drainage pipe discharging from the bottom of the housing A to take care of condensation and the like.

B is a substantially conical closure or cap which forms one side of the housing A and is held in position by the cap screws B¹. It contains adjacent its outer smaller end the oil chamber B², which chamber is bounded on the inner side by a partition wall B³. This wall B³, together with the main end wall of the cap, is provided with a circular central aperture in which is slidably mounted a bearing sleeve B⁴ to engage and support the end of the shaft A⁵. The outer end of this sleeve and of the shaft is covered by an integral cap B⁶ carried by the cap B. The sleeve B⁴ is provided with the slot C to permit the oiling ring C¹ to ride upon the shaft A⁵ and rotate with it, whereby as the shaft rotates oil may be picked up by the ring from the oil reservoir and carried to the top of the shaft to lubricate the shaft. A vane or flange C² projects inwardly from the wall of the cap B above the bearing sleeve B⁴ and overlies the slot C to prevent, when the parts are in the working position shown in Fig. 1, any accidental disarrangement of the oiling ring from the slot C such as might take place owing to jolting or other movement of the apparatus.

D is an assembly slot or aperture in the wall B³ through which the oiling ring C¹ may be introduced into the chamber B². It is loosely closed by the cap or shutter D¹.

D² is a spillway or overflow channel mounted on the wall B³ communicating at its

bottom through the port D³ with the interior of the chamber B² and discharging at its top to the port D⁴ into the interior of the housing A.

D⁵ is a grease or oil cup discharging into the chamber B² through which a suitable supply of oil or grease may be fed to lubricate the bearing.

It will be evident that while I have shown in my drawing an operative device, still many changes might be made in form, size, shape and arrangement of parts without departing materially from the spirit of my invention. I wish, therefore, that my drawing be considered as in a sense diagrammatic.

The use and operation of my invention are as follows: My device is assembled by first introducing the oiling ring through the assembly slot into the oil chamber. The bearing sleeve is then slowly forced into position in suchwise that it passes through the oiling ring and in suchwise that the oiling ring rests in the slot therein. The sleeve is then forced into the position shown in Fig. 1, whereupon the oiling ring is held loosely in the slot by the flange or vane above it. The rotor and shaft are then placed in the housing in the usual way, the shaft being supported at the other end by a bearing not shown and the conical head or wall is placed in position in such manner that the end of the shaft passes through the bearing sleeve and supports the oiling ring. The whole device is then tightened up and ready for use. Before the engine is started, of course, oil or grease or some fluid lubricant is introduced into the oil chamber and when steam is turned on to rotate the rotor, the shaft rotates, carrying the oiling ring, which in turn carries up the lubricant from the chamber to feed it to the shaft. It will be noted that no effort is made to pack the end of the shaft or otherwise prevent the discharge of air, steam or water of condensation from the turbine chamber into the oil chamber, though its egress from this chamber is prevented by means of a cap or grease cup. The result of this will be that the pressure in the two chambers will be the same and a certain amount of steam and water of condensation will find its way into the oil chamber. This water being, of course, of greater specific gravity than the oil will sink to the bottom of the chamber, and as the quantity increases it will be drawn off

through the overflow when the level of liquid in the chamber reaches a point higher than the level of the overflow, but owing to the fact that the water seeks the bottom of the chamber, it will be water which is discharged and not oil, and no harm will be done by this water, since it will be free to run off through the drip pipe as shown at the bottom of the turbine housing. When 10 it is desired to lay the machine up out of service, it is only necessary to add sufficient oil to the oil chamber to displace all the water and this may be done with perfect safety.

15 I claim:—

1. A turbine having a housing, an oil pocket located therein and in communication therewith, a bearing in said pocket and means for lubricating it and an overflow from said pocket communicating with the bottom thereof and discharging into the housing at the normal liquid level of the pocket.
2. In a turbine an oiling pocket, a bearing sleeve slidably supported in and extending through said pocket, an oil ring contained within said pocket and surrounding said bearing sleeve, said bearing sleeve being slotted, a shaft within said sleeve upon which the oiling ring rests as it lies in the slot in the sleeve and a flange overlying said slot to hold said ring in position.
3. In a turbine an oiling pocket, a bearing sleeve slidably supported in and extending through said pocket, an oil ring contained within said pocket and surrounding said bearing sleeve, said bearing sleeve being slotted, a shaft within said sleeve upon which the oiling ring rests as it lies in the slot in the sleeve and a flange overlying said slot to hold said ring in position, an assembly pocket in the wall of said pocket to permit introduction of the oiling ring and a cover therefor.
4. In a turbine, a two-part housing, one

part of said housing taking the form of a substantially conical cap, means for attaching it removably to the remainder of the housing, an oil pocket centrally located within said conical cap and a bearing sleeve 50 carried in said oil pocket.

5. In a turbine, a two-part housing, one part of said housing taking the form of a substantially conical cap, means for attaching it removably to the remainder of the 55 housing, an oil pocket centrally located within said conical cap and a bearing sleeve carried in said oil pocket, means located within said oil pocket carried by said sleeve for conveying oil from the bottom of the 60 pocket to said bearing.

6. In a turbine, a two-part housing, one part of said housing taking the form of a substantially conical cap, means for attaching it removably to the remainder of the 65 housing, an oil pocket centrally located within said conical cap and a bearing sleeve carried in said oil pocket, means located within said oil pocket carried by said sleeve for conveying oil from the bottom of the 70 pocket to said bearing, said pocket being in communication with the interior of the housing and an overflow communicating with the bottom of said pocket and discharging into said housing at the normal 75 liquid level of said pocket.

7. The combination with a bearing of an oil pocket surrounding it, means for lubricating said bearing from said oil pocket and an overflow from said pocket communicating with the bottom thereof and discharging at the normal liquid level thereof.

In testimony whereof, I affix my signature in the presence of two witnesses this 8th day of December 1913.

CHARLES W. DAKE.
